CIRCULAR LOOM

Frank Corbyn Hale and Robert Yeadon, Spandon,
near Derby, England, assignors to Celanese
Corporation of America, a corporation of
Delaware

Application October 4, 1935, Serial No. 43,540
In Great Britain October 19, 1934

2 Claims. (Cl. 139—16)

This invention relates to circular looms and in particular to circular looms and shuttles for use therein. The invention is particularly concerned with circular looms of the type in which the shuttles are positioned within the shed by means of vane wheels engaging flanged rollers rotatably mounted in the shuttle body, for example of the type described in U. S. application S. No. 706,322 filed 12th January 1934. Shuttle-positioning means of this type enable the shuttle to be firmly and accurately positioned while permitting free passage of one sheet of warp threads past the side of the shuttle at which the vane wheels lie, the continued rotation of the vane wheels in one direction presenting slots into which the threads of that sheet enter as they encounter the wheels.

It is important in circular looms that upon faulty shedding such as is occasioned by broken or jammed warps, weaving should be brought rapidly to an end, and in looms of the type mentioned, provision is made for the relative motion between the shuttles and warps to cease on such an occurrence. Thus, in a loom in which the warps are stationary while the shuttles rotate the member carrying the vane wheel shafts is rapidly brought to rest, the rotation of the vane wheels themselves ceasing at the same moment. It has been found, however, that the extremely rapid stoppage of the rotation of the vane wheels sometimes causes a slight backward movement of these wheels, probably owing to backlash in the driving arrangement, and this backward rotation may cause the vane wheels to carry the warp threads towards the lower set of flanged rollers in the shuttles and so break or otherwise damage the threads.

The present invention overcomes this difficulty by means of a guard mounted on the shuttle body near to the points of engagement of the vane wheels with the lower flanged rollers, so as to resist the tendency of the vane wheels to carry the threads inwardly towards the rollers. Thus, the guard may take the form of a flat plate or strip extending horizontally of the shuttle body in close proximity to the flanges of the two lower rollers, the flat plate extending outwardly from the plate carrying the frame in which the rollers are mounted, to a point in or near to the normal line followed by the one sheet of warps. The flat plate thus forces the warp threads on the one side of the shuttle to keep substantially to their normal line in spite of any tendency for backward rotation of the vane wheels to carry

them out of that line towards the flanged rollers. The flat plate may conveniently be provided with ears or lugs by which it can be secured to the shuttle body.

Another form of guard comprises a stiff wire secured at its two ends to the shuttle body and extending lengthwise of the body and outwardly therefrom to a point in or near to the normal line of the one sheet of warp threads, in the same manner as the plate. Like the plate, the wire guard maintains the warp threads on the one side of the shuttle substantially in their normal line in spite of any tendency for backward rotation of the vane wheels to carry the threads out of that line towards the flanged rollers.

A form of apparatus according to the invention will now be described in greater detail with reference to the accompanying drawing in which

Fig. 1 is a front elevation of a shuttle;

Fig. 2 is a section on the line 2—2 of Fig. 1 showing the shuttle as mounted in operative position; and

Fig. 3 is a section taken on the line 3—3 of Fig. 1.

The shuttle comprises a top plate 4 and an intermediate plate 5 carrying between them a plate 6 for the support of a spool 7 and a plate 8 having a frame 9 on which rollers are supported by which the shuttle is positioned in the shed. Thus, there are two pairs of horizontally-disposed flanged rollers 10 for engagement with a pair of rotatable vane wheels 11 mounted on a shaft 12 and a substantially vertical roller 13 for engagement with a race 14 on the opposite side of the shuttle to the shaft 12. The normal, or forward direction of rotation of the vane wheels 11 is indicated by the arrow, this direction being anti-clockwise as viewed in Fig. 2. Weft 35 unwinding from the spool 7 is led downwardly to a guide eye 34 from which the weft passes into the fabric.

Warp threads proceeding downwards to the shuttle are shedded into an outer sheet 15 and an inner sheet 16, the threads of the outer sheet passing through the slots in the vane wheel 11 to the base of the shuttle, and the inner sheet 16 passing between the roller 13 and the race 14 to meet the sheet 15 at the base of the shuttle.

Mounted on the plate 8 is a narrow strip 17 at a level just below the point of engagement of the vane wheel 11 with the lower pair of flanged rollers 10. The strip 17 has a pair of ears 18 bent downwards to form angles by which the strip is secured to the plate 8, conveniently by the same screws 19 as are used to secure the

frame 9 to the plate 8. The outer sheet of warps 15 rests against the outer edge of the strip 17 and is prevented by the strip from being carried into the nip of the vane wheel 11 and the lower 5 rollers 10 in the event of any backward rotation of the vane wheel, viz. in the direction opposite to that indicated by the arrow.

In order to avoid there being any crevice between the forward end of the strip 17 and the 10 plate 8 into which the warp threads might enter, a hole 20 is formed in the plate 8 and the front end 21 of the strip 17 is bent into the hole as shown in Fig. 3.

The strip 17 is shown applied to a shuttle having 15 an adjustable base for regulating the pressure of the shuttle on the weft laid in the fabric. Below the plate 8 is mounted a plate 22 forming the base of the shuttle, the edge 23 of the plate 22 lying at the fell of the fabric 24 to press weft 20 25 laid by a preceding shuttle firmly into the fabric. The base 22 is pivotally mounted at 26, the pivot shown being formed in a plate 27 bent round the plate 8 and base member 22 so as to prevent the formation of any crevice for the entry 25 of warp threads.

A link comprising oppositely-threaded members 28, 29, a similarly threaded sleeve 30 and lock nut 31 is connected at the points 32, 33 to the plate 8 and base member 22 respectively and 30 provides for adjustment of the position of the edge 23 of the base member 22.

What we claim and desire to secure by Letters Patent is:—

1. Circular loom shuttle adapted to be positioned within the warp shed by rotatable vane wheels which pass through one warp sheet into contact with the shuttle, the threads of that sheet passing through the slots of the vane wheels, said shuttle comprising a top plate and 35 an intermediate plate fitting within the warp shed with their edges substantially at right-angles to the warp threads, a spool-supporting plate connecting said top plate and said intermediate plate, a further plate extending from said intermediate plate and adapted to press with its 40 edge against weft in the fabric, pairs of flanged

rollers supported in said further plate for engagement by said vane wheels, and a guard plate mounted on said further plate near the points of engagement of said vane wheels with said flanged rollers and between said flanged rollers 5 and the weft-pressing edge of said further plate, the edge of said guard plate extending to a point substantially in the line of the warp threads from the edge of said intermediate plate to the weft-pressing edge of said further plate so as to 10 resist any tendency of the rotatable vane wheels to carry the warp threads inwardly towards said flanged rollers.

2. Circular loom shuttle adapted to be positioned within the warp shed by rotatable vane 15 wheels which pass through one warp sheet into contact with the shuttle, the threads of that sheet passing through the slots of the vane wheels, said shuttle comprising a top plate and an intermediate plate fitting within the warp 20 shed with their edges substantially at right-angles to the warp threads, a spool-supporting plate connecting said top plate and said intermediate plate, a further plate extending from said intermediate plate and adapted to press with its 25 edge against weft in the fabric, pairs of flanged rollers supported in said further plate for engagement by said vane wheels, and a guard plate mounted on said further plate near the points of engagement of said vane wheels with said 30 flanged rollers and between said flanged rollers and the weft-pressing edge of said further plate, the forward edge of said guard plate being curved so as to fit into a hole formed in the further plate 35 in order to prevent the formation of any crevice between the guard and the shuttle body into which warp threads can enter, and extending from such forward edge to a point substantially in the line of the warp threads from the edge of said intermediate plate to the weft-pressing edge of 40 said further plate so as to resist any tendency of the rotatable vane wheels to carry the warp threads inwardly towards said flanged rollers.
